UNITED STATES PATENT OFFICE.

GAILLARD E. WEAVER AND EDWARD W. KELLEY, OF SPRINGFIELD, ILLINOIS, AS
SIGNORS TO WEAVER MANUFACTURING COMPANY, OF SPRINGFIELD, ILLINOIS, A
CORPORATION OF ILLINOIS.

TIRE SPREADER.

Application filed July 16, 1927. Serial No. 206,356.

The present invention relates to certain novel structural and operating advantages in appliances for opening up or spreading tire-casings for inspection and repair purposes.

One object of the invention is to provide an apparatus of this character in which the opposed bead or margin engaging hooks or fingers will first travel directly downwardly into the space between such margins before beginning their spreading or separating operation, thus assuring a proper and suitable initial interlocking of the parts preliminary to the following separating or opening action, and also adapting the device for satisfactory service with tire-casings covering a substantial range of sizes.

A further aim of the invention is the production of a machine of this kind of simple type and form, and which may be manufactured relatively economically and operated with the expenditure of a small amount of energy.

Other advantages accruing from the new and improved structure will become apparent to those skilled in this art from an understanding of the preferred embodiment of the invention presented in the accompanying drawings forming a part of this specification and throughout the views of which like reference numerals have been employed to designate the same structural elements.

In these drawings,—

Fig. 1 is a perspective view of the new appliance with its parts in inoperative position;

Fig. 2 is a similar view of the structure, with the hooks separated, ready for the introduction of a tire-casing between them;

Fig. 3 is a perspective view showing a tire-casing spread for inspection purposes on the apparatus; and

Fig. 4 shows the different positions occupied by the spreading hooks in the performance of their functions.

Referring to these drawings, it will be perceived that the appliance includes a frame made of four, inclined, corner, angle-posts 11, 12, 13 and 14, fastened at their upper ends to a longitudinally and transversely curved support or form member 15 over which the tire-casing 16 is adapted to be spread or partially turned inside out to permit ready inspection of its inside surface for the detection of faults and injuries, the rear legs or posts 12 and 13 being secured together by a lower

horizontal angle-bar 17 and an upper rod 18, 55 the front legs 11 and 14 being joined together by a bottom bar 19, a similar intermediate bar 21, and a tie rod or shaft 22, the pairs of legs, 11 and 12, and 13 and 14, being fastened together and the frame structure suitably strengthened and stiffened by horizontal end-bars 23 and cross, inclined brace-bars 24, 24.

A forwardly-extended foot-lever or pedal 25 is fulcrumed at its rear end at 26 to brackets mounted on the back, lower bar 17, such pedal having its front part twisted through ninety degrees to provide an accessible, integral foot-piece 27, such lever also having a loop 28 around a toothed or notched locking-bar 29 fastened at its lower and upper ends to 70 the frame members 19 and 21, the pedal being shaped to provide a lip 31 which is adapted to fit in any one of the recesses of the locking-bar 29 to maintain the pedal or treadle in appropriate depressed position, a coiled 75 spring 32 fastened to such lever and to the rod or shaft 18 constantly tending to rock the pedal upwardly to its limit of movement.

At 33, the lower ends of two bent arms 34 and 35, front and rear, respectively, are pivotally connected to opposite sides of the pedal 25 at about the middle of its length, the upper end of each such arm having a pair of spaced hooks 36, 36 integral and rigid therewith and adapted to perform the tire-casing spreading operation, such hooks or curved fingers on the arm 34 extending rearwardly, whereas the complementary hooks of the arm 35 project forwardly, all as is fully illustrated.

The bent arm 34 is slotted at 37 for the reception of a laterally-projecting pin or stud 38 on the end of the longer arm 39 of a bell-crank lever fixed to or rockably mounted on the rear shaft 18, the shorter arm 41 of such lever being connected by an equalizing-link 42 to a projection 43 of a lever 44 fixed to or rockable on the front shaft 22, and having a side pin 45 at its upper end slidable in a slot 46 in the arm 35, such slot, of course, being the counterpart of the slot 37 of the companion arm.

To prevent the front and rear shafts 22 and 18 from spreading apart due to the strain imposed upon them, they are connected together near their centers by a pair of appropriately-apertured tie-rods 47, 47 joined together at their ends beyond the two shafts by bolts 48 equipped with spacing sleeves or

spools 49 between the parallel members 47, 47.

When the appliance is not in operation, it presents the appearance depicted in Fig. 1, the parts assuming the positions illustrated 5 due to the lifting action of the spring, the downwardly-disposed, free ends of the front and back hooks 36, 36 being closely adjacent, as shown, and, under these conditions, the pins 38 and 45 occupy a substantially middle 10 position in their respective slots 37 and 46.

When it is desired to mount a tire-casing 16 on the device, the operator pulls the front arm 34 and its pair of spacing hooks 36 forwardly, and, owing to the link connection 15 42 between the complementary arms 34 and 35, this causes a simultaneous and equal backward swing of arm 35 and its hooks, such separation of the hooks being permitted because of the pin-and-slot connections, the 20 pedal under these circumstances remaining stationary, and, when the hooks have been thus spaced apart for the accommodation of the tire-casing between them, the pin 38 will occupy the rear part of its slot 37, and the corner-related pin 45 will be in the front portion of its slot 46, as shown in Fig. 2.

The casing to be inspected having been introduced between the spaced hooks and permitted to rest on the top of the support 15, 30 the operator releases the front arm, whereupon the front and rear hooks come together again above the gap between the borders or margins of the casing.

Upon subsequent depression of the pedal, 35 during their initial movement, all of the hooks move directly downwardly into such gap, thus assuring their effective hold on the margins of the tire-casing during their further spreading action.

40 As soon, however, as the pin 38 reaches the front end of its slot 37, which will be coincident with the travel of the pin 45 at the back end of its slot 46, the direct or vertical descent of the hooks terminates, and, thereafter, 45 the two pairs of hooks separate as they descend, such spreading being positively effected by the downwardly-rocking, crossed levers 39 and 44, whose pins are then bearing against the end walls of their respective slots.

50 Thus the hooks automatically enter the space between the edges of the casing and thereafter spread the casing in ample degree for inspection purposes, as shown in Fig. 3, the casing being maintained in this condition 55 as long as desired by the coaction of the pedal-lip 31 with the corresponding notch of the holding bar 29.

The paths of travel of the hooks are indicated by their several dotted-line positions, 60 as shown in Fig. 4.

When it is desired to release the tire-casing, possibly for the similar inspection of an adjacent portion thereof, the pedal is pushed slightly sidewise to free it from the holding 65 bar, and then the contraction of the pre-

viously-elongated spring 32 brings the parts back to original position, enabling the workman to turn the casing around its own axis for the inspection of a new portion thereof, or permitting the workman to again separate 70 the hooks, by hand, as previously, to remove the tire-casing.

From the foregoing it will be obvious that the apparatus is simple in structure and easily operated, its few parts tending to economy in manufacture and avoidance of likelihood of 75 their damage or injury in ordinary service.

Also, it will be observed from its structure and manner of functioning that it will accommodate tirecasing of various sizes and 80 spread them in satisfactory manner.

Although the appliance has been shown and described as being operated by a pedal, it will be understood that the same principles of construction may be employed in a hand-operated apparatus and without departure from the substance and essence of the invention as defined by the appended claims.

Or, stated somewhat differently, the invention is susceptible of a variety of embodiments differing more or less in mechanical details but all incorporating the fundamental principles of the new structure.

We claim:

1. In a tire-casing spreader, the combination of a support for the tire-casing to be spread, hook-members adapted to engage the opposite margins of a tire-casing mounted on said support, and means to move said hook-members to cause them to enter the gap between said margins without substantial separation and then to separate to perform their tire-casing spreading action.

2. In a tire-casing spreader, the combination of means to support the tire-casing, hook-members adapted to engage the opposite margins of a tire-casing mounted on said supporting means, means to depress said hook-members, and means having loose connection with said hook-members causing them during 105 their initial movement to enter the gap between the tire-casing margins without substantial separation and during their further movement causing them to separate to perform their tire-casing spreading function.

3. In a tire-casing spreader, the combination of means to support the tire-casing, an operating-lever, hook-members rockingly connected at their lower ends to said lever, their upper ends being adapted to engage the opposite margins of a tire-casing mounted on said supporting means, and means having loose connection with said hook-members causing them during their initial movement effected by the depression of said lever to enter the gap between the tire-casing margins without substantial separation and during their further movement causing them to separate to perform their tire-casing spreading function.

4. In a tire-casing spreader, the combina-

tion of a tire-casing support, an operating lever, rigid hook-members rockingly connected at their lower ends to said lever, their upper ends being adapted to engage the opposite margins of a tire-casing mounted on said support, and means having loose connection with said hook-members causing them during their initial movement effected by the depression of said lever to enter the gap between the tire-casing margins without substantial separation and during their further movement causing them to separate to perform their tire-casing spreading function.

5. In a tire-casing spreader, the combination of a frame, a tire-casing support on said frame, hook-members adapted to engage the opposite margins of a tire-casing mounted on said support, means to move said hook-members downwardly, and links fulcrumed on said frame and each having a loose connection with its corresponding hook-member, thereby causing the hook members during their initial movement to enter the gap between the tire-casing margins without substantial separation 25 and during their further movement causing them to separate to perform their tire-casing spreading function.

6. In a tire-casing spreader, the combination of a frame, a tire-casing support on said frame, rockingly-mounted rigid hook-members adapted to engage the opposite margins of a tire-casing mounted on said support, means to move said hook members downwardly, and links fulcrumed on said frame and each having a loose connection with its corresponding hook-member, thereby causing the hook members during their initial movement to enter the gap between the tire-casing margins without substantial separation and 40 during their further movement causing them to separate to perform their tire-casing spreading function.

7. In a tire-casing spreader, the combination of a frame, a tire-casing support on said frame, an operating lever rockingly mounted on said frame for movement in a vertical plane, rigid hook-members adapted to engage the opposite margins of a tire-casing mounted on said support and rockingly 50 connected to said operating lever, and links fulcrumed on said frame and each having a loose connection with its corresponding hook-member, thereby causing the hook-members during their initial movement to enter the gap between the tire-casing margins without substantial separation and during their further movement causing them to separate to perform their tire-casing spreading function.

8. In a tire-casing spreader, the combination of a frame, a tire-casing support on said frame, hook-members adapted to engage the opposite margins of a tire-casing mounted on said support, means to depress said hook-

members, and means having loose connection with said hook-members permitting the latter to be separated manually without actuation of said depressing means to allow the introduction of a tire-casing between them and causing said hook-members during their initial movement to enter the gap between said tire-casing margins without substantial separation and during their further movement causing said hook-members to separate to perform their tire-casing spreading function.

9. In a tire-casing spreader, the combination of a frame, a tire-casing support on said frame, a pedal fulcrumed on said frame to rock in a vertical plane, a pair of arms rockingly connected to said pedal, hook-members rigid with said arms adapted to engage the opposite margins of a tire-casing mounted on said support, and means coacting with said arms causing the hook-members upon depression of the pedal to descend vertically without substantial separation into the gap between the tire-casing margins and then upon further descent of the pedal to compel the separation of said arms and hook-members to perform the tire-casing spreading function.

10. In a tire-casing spreader, the combination of a frame, a tire-casing support on said frame, a pedal fulcrumed on said frame to rock in a vertical plane, a spring tending to rock said pedal upwardly, means to lock said pedal in a plurality of depressed positions, a pair of bent arms hinged to said pedal, hook-members rigid with said arms adapted to engage the opposite margins of a tire-casing mounted on said support, a first link hinged on said frame and having a slot-and-pin connection with one of said arms, a second link hinged on said frame and having a slot-and-pin connection with the other arm, and an equalizer connection between said links, 95 said pins occupying an intermediate position in their respective slots when the hook-members of the two arms are practically closed together, whereby by swinging one arm and its hook-member outwardly the other arm and its hook-member will rock in the opposite direction simultaneously and substantially the same amount, such slot-and-pin connections upon depression of the pedal permitting said hook-members to descend practically vertically without separation to enter the gap between the tire-casing margins until the pins reach the ends of their slots, whereupon further downward movement of the pedal causes the separation of the arms and hook-members 105 and the spreading of the tire-casing.

In witness whereof we have hereunto set our hands.

GAILARD E. WEAVER.
EDWARD W. KELLEY.
